UNITED STATES PATENT OFFICE.

ROBERT ZAHN, OF PLAUE, GERMANY.

EMBROIDERY-MACHINE.

1,016,194.

Specification of Letters Patent.

Patented Jan. 30, 1912.

Application filed March 11, 1911. Serial No. 613,856.

To all whom it may concern:

Be it known that I, ROBERT ZAHN, a subject of the King of Bavaria, residing at Plauen, Vogtland, in the Kingdom of Saxony, Germany, have invented certain new and useful Improvements in Embroidery-Machines, of which the following is a specification.

It is well known, that when the rectangular fabric frame is of considerable length, the motion of the portions of the frame remote from the point where the pantograph or the jacquard mechanism is attached, are not the same in direction or extent as those of the part of the frame adjacent to the point of attachment of the pantograph or jacquard mechanism, in consequence of which the embroidery often shows faults.

The object of my invention is to obviate these drawbacks and to provide means whereby the up and down movement of the long frame will be absolutely uniform and forcible upon its entire length.

One embodiment of my invention is illustrated in the accompanying drawing which forms a part of this specification.

In well known manner, the fabric frame 1 is properly suspended by means of rollers 2 from angular levers 3, 4 suitably connected together as by means of a rod 5 or the like and of which one, as 3 carries a counter-weight 6, whereby the frame is balanced. Arranged at one end and at several intermediate points in the direction of the length 35 of the frame are the supporting pins 7, 8, 9. In the present example two intermediate supporting pins are shown. Engaging with these pins are the horizontal loops 10, 11 and 12 carried by the vertical slides 13, 14, 15 respectively. The slides are each provided with a lateral rack, as 13', 14', 15' respectively, which are in meshing connection with pinions 16, 17, 18 respectively. These pinions, which are journaled in brackets fixed in the frame 19 of the machine are

simultaneously in meshing connection with a common rack 20 extending longitudinally of the fabric frame.

The transmission of motion to the fabric frame is effected at the point 21 from the jacquard mechanism J in well known manner, as for instance, in the manner shown and described in my prior application, 542,305, filed February 5, 1910.

It will be seen, that the vertical motion of the slide 13 received from the jacquard mechanism will impart rotation to the pinion 16, which through the common longitudinal rack 20 will be simultaneously transmitted to the other pinions 17, 18. From these pinions, the intermediate vertical slides 14, 15 will receive a vertical motion that will perfectly correspond to that of the slide 13.

What I claim and desire to secure by Letters Patent is:

1. In embroidery machines, the combination with the fabric frame, of a plurality of supporting members on said frame arranged longitudinally thereof, a number of vertically slideable toothed guiding members 70 engaging the said supporting members, a gear for each guiding member meshing with the teeth thereof and a common rack simultaneously meshing with all said gears.

2. In embroidering machines, the combination with a fabric frame, of a plurality of supporting pins on said frame arranged longitudinally thereof, a number of vertically slideable looped guiding members formed with lateral racks and engaging the 80 said supporting pins, a gear for each guiding member meshing with the rack thereof and a common rack simultaneously meshing with all said gears.

In testimony whereof I affix my signature in presence of two witnesses.

ROBERT ZAHN.

Witnesses.
